ELECTRIC CIGAR LIGHTER

Arthur A. Johnson, Bridgeport, Conn., assignor
to Automatic Devices Corporation, Bridgeport,
Conn., a corporation of Connecticut

Application November 8, 1934, Serial No. 752,084

25 Claims.

(Cl. 219—32)

This invention relates to electric cigar-lighters, and more particularly, to the type of lighter which is completely removable from the base or holding device for use.

With this type of cigar-lighter, the igniting unit is in normal position on the holding device in the open-circuit relation thereto. When it is desired to use the lighter, the igniting unit is moved relative to the holding device to an energizing position where the circuit from the heating element is closed. Usually it is held by hand in this position until the heating element is incandescent and ready for use.

An object of this invention is to provide an electric cigar-lighter of the type referred to in which the igniting unit will be held in energizing position automatically for a predetermined time during which the heating element is brought to incandescence for use.

In the form of the invention herein illustrated, this is accomplished by latching the igniting unit in energizing position against the tendency of a spring to return it to open-circuit position and at the same time exhausting air from a chamber, and then allowing the air to gradually enter the chamber so that the air may expand and finally release the latch.

A feature of this invention is the provision of means whereby the igniting unit will be moved to non-energizing position when the heating element attains a predetermined temperature if the igniting unit should fail to return under the control of said time-controlled means.

This is accomplished in the form of the invention herein illustrated, by providing a thermostatic device in heat conducting relation to the igniting unit and causing the thermostat to open the air chamber to the atmosphere and allow the igniting unit to move to energizing position.

This is a particularly important feature, for, with a time-controlled device, the operator may hold the igniting unit in energizing position and initiate the heating of the coil. After its manual release the igniting unit would remain in energizing position for a predetermined length of time controlled by the time-controlled mechanism, and this might cause the heating coil to overheat and burn out. With the provisions of the present invention, should the heating element tend to overheat, the thermostatic safety device will open the air chamber and permit the chamber to rapidly expand and allow the igniting unit to return to non-energizing position.

Other features and advantages will hereinafter appear.

In the accompanying drawings—

Figure 1 is a longitudinal sectional view of the cigar-lighter of the present invention, showing the igniting unit in normal inactive position on the holding device.

Fig. 2 is a similar view, but showing the head or button of the igniting unit partially depressed to exclude the air from the time control mechanism.

10 Fig. 3 is a view similar to Figs. 1 and 2, but showing the head or button of the igniting unit completely depressed, and showing the igniting unit locked in energizing position.

Fig. 4 is a view similar to Figs. 1 and 2, but 15 showing the heating element locked in energizing position and the time control mechanism partially returned to normal position and about to release the heating element which by this time has been brought to incandescence for use.

20 Fig. 5 is an end view of the igniting unit partially broken away to show one of the relief valves to permit exclusion of the air between the cylinder and piston of the time control mechanism.

Fig. 6 is an elevation of the igniting unit of the 25 present invention.

Fig. 7 is a view of the inner end of the igniting unit body showing a thermostatically controlled valve.

Fig. 8 is an exploded view partially in section 30 of the inner end of the igniting unit, showing in detail the feature shown in Fig. 7.

The present invention in the form illustrated herein as exemplary thereof, has a shell-like holding device 10, the forward end of which extends through a suitable support such as an instrument board 11 and is threaded to receive a clamping ring 12 and a lock nut 13 by means of which it is held in position on the support 11. The rear end of the shell is closed by a head 14 over which there is located an insulating block 15 supporting contact arms 16. These arms are integral and are held in the head by a screw 17, the end of which has nuts 18 for securing a terminal 19 of a current supply wire. When the cigar-lighter is used on the instrument board of an automobile, the board being grounded, current is conducted to the shell 10 through the ground connections.

The igniting unit of the present invention is 50 completely removable from the holding device for use. It comprises a heating element 20 supported on the end of a cylinder 21 which may be of metal or insulating material as desired. The sleeve 21 has a sliding fit in the shell 10 and when 55 it is moved inwardly as far as it will go, it carries

the heating element 20 toward the contacts 16 so that a ferrule 22 on the heating element electrically engages the contact arms 16 and connects the outer convolution of a heating coil 23 to the terminal 19. This movement of the igniting unit cylinder 21 is resisted by a spring 24 located between the end of the igniting unit and the insulating block 15, and the tendency of the spring is to return the heating element from the energizing position shown in Fig. 3 to the normal position shown in Fig. 1. Usually, the cylinder 21 or its equivalent is moved from the position shown in Fig. 1 to the position shown in Fig. 3, and held there manually until the heating element becomes incandescent and is ready for use.

According to the present invention, the heating element is held in its energizing position (shown in Fig. 3) automatically, and for this purpose there is provided a latch 25 secured at its rear end to the shell 10 and having a projection or tooth 26 in position to engage the front end 27 of the cylinder 21 as shown in Fig. 3, the latch being made of resilient material so as to spring into the position shown in Fig. 3 when the forward end of the cylinder 21 occupies the position shown in that figure.

To move the igniting unit cylinder 21 from the position shown in Fig. 1 to that shown in Fig. 3, there is provided a piston 28 slidable within the cylinder 21 and having a shoulder 29 engaging the end 27 of the cylinder 21. The piston 28 has at its forward end a head or button 30 of any suitable material. When the button 30 is pushed inwardly to the end of its movement, the shoulder 29 engages and moves the cylinder 21 to carry the heating element into engagement with the contact 16.

In moving from the position shown in Fig. 1 to that shown in Fig. 2, the piston 28, which has a sliding fit with the cylinder 21, expels the air in the chamber C between the end of the piston and the end of the cylinder through one or more openings 31 in the end wall 32 of the cylinder, which action is permitted because the valves 33, (see Fig. 5) which are riveted to the end wall 32 of the cylinder, and resiliently close the ports 31, will yield and permit the passage of air from the chamber C.

At the same time that the air in expelled from the chamber C, a spring 34, located in a tube 35 secured to the end of the piston 28, is placed under compression as shown in Fig. 2, the spring being confined between the end of the tube 35 and the end of a plug 36 carried by the end wall 32 of the cylinder 21.

Accordingly, when the button 30 is manually released after the parts have been moved to the positions shown in Fig. 3, the spring 34 tends to move the piston 28 to the right as shown and may do so as quickly as air is allowed to enter the chamber C. The quantity of air which may enter the chamber C may be determined by the clearance between the cylinder and piston, or may be regulated in any suitable way. For instance, as shown in Fig. 4, the cylinder may be provided with an inlet opening 37, the size of which is controlled by a set screw 38 and the regulation of the screw 38 will determine the length of time it requires for the piston and cylinder to completely expand.

As the piston moves outwardly under the influence of the spring 34, an annular rib 39 on the piston approaches and engages a projecting portion 40 on the latch spring 25 as shown in Fig. 4. A continued movement of the piston 28

5 to the right will cause the spring 25 to be depressed and the lug 26 thereon to disengage the end 27 of the cylinder, whereupon the spring 24 is free to return the igniting unit as a whole from the position shown in Figs. 3 and 4 to that shown in Fig. 1.

It will be noted that the movement of the cylinder and piston is gradual but that the movement of the heating element 20 away from the contact springs 16 will be sudden, and therefore the circuit will be quickly opened and the drawing of an arc from the contacts 16 to the heating element ferrule 22 will be avoided.

To limit the movement of the piston outwardly 15 of the cylinder under the influence of the spring 24, the plug 36 is provided with an extension rod 41 carrying a stop flange 42 held in position by nuts 43. Therefore, when the igniting unit is to be removed from the holding device after it is in 20 condition for use, pulling movement on the button 30 will cause the entire igniting unit to be removed from the holding device.

As above pointed out, current is supplied to the outer convolution of the heating element from the wire lug 19 through the contacts 16 which are made to yield so that the end 27 on the cylinder 21 may sufficiently pass the latch 25. The inner convolution of the heating element is connected to a post 44 threaded in the 30 plug 36 which in turn has sliding engagement with the tube 35 threaded in the piston 28, all of which connections are metallic and conduct current to the inner convolution of the heating coil. The piston 28 has a flange 45 having sliding engagement with the shell 10 which, as 35 stated, is connected to the instrument board, and thus current is conducted from the ground through the instrument board, shell 10, and piston 28 to the heating element.

It will thus be seen that the present invention provides means for moving the heating element out of energizing position after a predetermined time. This time is regulated and determined so that the heating element will be 40 incandescent and ready for use when the igniting unit moves from the position shown in Fig. 3.

It may be that the person using the device instead of depressing the button 33 to the limit of its movement and immediately releasing the 45 same might hold the button depressed for some time during which the heating element would be energized and begin to heat. Upon releasing the button, the time control means would begin to function and the result would be that the heating element was maintained in energizing position a greater length of time than is desirable with the attendant danger of becoming overheated and possibly burning out.

To avoid this, the present invention provides 50 means for quickly admitting air to the chamber C when the heating element reaches a predetermined temperature. Means for this purpose is shown in Figs. 7 and 8, wherein the flap valve 46 is made of bimetallic material. The material employed is so chosen and the length of the flap so calibrated that the valve 46 does not uncover the outer port 31 when the heating element is brought to normal incandescence for use but will move and uncover the port 31 when the temperature of the heating element exceeds a predetermined value. When the valve 46 uncovers the port 31, air is rapidly admitted to the chamber C and the heating element is moved to non-energizing position.

Variations and modifications may be made

within the scope of this invention and portions of the improvements may be used without others.

Having thus described the invention, what I claim as new and for which I desire to obtain Letters-Patent is—

1. An electric cigar-lighter having a holding device and an igniting unit mounted on the holding device for complete removal for use, said igniting unit including a heating element; manually operable means for closing a circuit to said heating element; means including fluid-operated timing means for automatically opening said circuit a predetermined time after said circuit is manually closed; and auxiliary means for opening the circuit in response to the temperature of the heating element.

2. An electric cigar-lighter having a holding device and an igniting unit mounted on the holding device for complete removal for use, said igniting unit including a heating element; cooperating contacts on the holding device and igniting unit for closing a circuit including said heating element, said igniting unit having a normal position on the holding device in which said circuit through said heating element is open and being manually movable to position to cause said cooperating contacts to engage and close the circuit through said heating element; means for retaining said igniting unit in circuit-closing position; means including fluid operated timing means to release said retaining means for automatically opening said circuit a predetermined time after said circuit is manually closed; and auxiliary means for opening the circuit in response to the temperature of the heating element.

3. An electric cigar-lighter having a holding device and an igniting unit mounted on the holding device for complete removal for use, said igniting unit including a heating element; cooperating contacts on the holding device and igniting unit for closing a circuit including said heating element, said igniting unit having a normal position on the holding device in which said circuit through said heating element is open and being manually movable to position to cause said cooperating contacts to engage and close the circuit through said heating element; a latch for holding the igniting unit in energized position; a spring tending to return the igniting unit to non-energized position; a cylinder and piston from which air is expelled during the movement of the igniting unit to energized position; means tending to separate the cylinder and piston; an air inlet permitting air to gradually enter between the cylinder and piston; and means on said piston to engage and release said latch when the piston has moved outwardly of the cylinder a predetermined amount and permit the igniting unit to move to non-energized position in which the circuit through the heating element is opened.

4. An electric cigar-lighter having a holding device and an igniting unit mounted on the holding device for complete removal for use, said igniting unit including a heating element; cooperating contacts on the holding device and igniting unit for closing a circuit including said heating element, said igniting unit having a normal position on the holding device in which said circuit through said heating element is open and being manually movable to position to cause said cooperating contacts to engage and close the circuit through said heating element; a latch for holding the igniting unit in energized position;

a spring tending to return the igniting unit to non-energized position; a cylinder and piston from which air is expelled during the movement of the igniting unit to energized position; means tending to separate the cylinder and piston; an air inlet permitting air to gradually enter between the cylinder and piston; means on said piston to engage and release said latch when the piston has moved outwardly of the cylinder a predetermined amount and permit the igniting unit to move to non-energized position in which the circuit through the heating element is opened; an auxiliary air inlet; and a heat responsive member in heat-conducting relation to said heating element to admit air to said cylinder when the heating element reaches a predetermined temperature.

5. An electric cigar-lighter having a holding device and an igniting unit mounted on the holding device for complete removal for use, said igniting unit including a heating element; cooperating contacts on the holding device and igniting unit for closing a circuit including said heating element, said igniting unit having a normal position on the holding device in which said circuit through said heating element is open and being manually movable to position to cause said cooperating contacts to engage and close the circuit through said heating element; means for retaining said igniting unit in circuit-closing position; time-controlled means for automatically opening said circuit and returning said igniting unit to normal open position; and means in heat-conducting relation with said heating element for causing said igniting unit to be moved to normal open-circuit position when the heating element has been brought to a predetermined temperature.

6. An electric cigar-lighter having a holding device and an igniting unit mounted on the holding device for complete removal for use, said igniting unit including a heating element; cooperating contacts on the holding device and igniting unit for closing a circuit including said heating element, said igniting unit having a normal position on the holding device in which said circuit through said heating element is open and being manually movable to position to cause said cooperating contacts to engage and close the circuit through said heating element; means for retaining said igniting unit in circuit-closing position; pneumatic time-controlled means for automatically opening said circuit and returning said igniting unit to normal open circuit position; and thermostatic means in heat-conducting relation with said heating element for causing said igniting unit to be moved to normal open-circuit position when the heating element has been brought to a predetermined temperature.

7. An electric cigar-lighter having a holding device and an igniting unit mounted on the holding device for complete removal for use, said igniting unit including a heating element; cooperating contacts on the holding device and igniting unit for closing a circuit including said heating element, said igniting unit having a normal position on the holding device in which said circuit through said heating element is open and being manually movable to position to cause said cooperating contacts to engage and close the circuit through said heating element; a latch for holding the igniting unit in energized position; a spring tending to return the igniting unit to non-energized position; time-controlled means

for automatically releasing said latch; and thermostatic means in heat-conducting relation with said heating element for automatically releasing said latch when the heating element has been brought to a predetermined temperature.

3. An electric cigar-lighter having a holding device and an igniting unit mounted on the holding device for complete removal for use, said igniting unit including a heating element; manually operable means for closing a circuit to said heating element; means independent of the heat produced by the heating element for automatically opening said circuit a predetermined time after said circuit is manually closed; and means in heat-conducting relation with said heating element for automatically opening said circuit when the heating element has been brought to a predetermined temperature.

9. An electric cigar-lighter as in claim 1, wherein said timing means includes a fluid chamber within which fluid is compressed on operation of said manually operable means, and a valve permitting loss of compression by said fluid at a slower rate than the rate of compression thereof.

10. An electric cigar-lighter as in claim 1, wherein said timing means includes a fluid chamber within which fluid is compressed on operation of said manually operable means, and a valve permitting loss of compression by said fluid at a slower rate than the rate of compression thereof, there also being means including a thermostat for causing such compression loss at a faster rate following attainment by said heating unit of a certain temperature.

11. In a cigar lighter, a base; a member mounted on the base for movement relatively thereto; means for yieldingly urging said member to a given normal position relatively to the base; manually engageable means, to move said member to a second position relatively to the base, against the urging of said yielding means; means controlling the speed of said member in returning to its normal position under the urging of said yielding means, to delay the completion of said return a predetermined time; a second movable member relatively movable to but operatively connected with the first and moved thereby to a given circuit-closing position when said first member is moved against the urging of said yielding means; means for holding said second member in its circuit-closing position; a heating element; means for closing a circuit through the heating element when the second member is in said circuit-closing position; and means for moving said second member to its initial position, to open the circuit through the heating element, when the said first member completes its return to normal position and releases the holding means.

12. In a cigar lighter, a base; a member mounted on the base for movement relatively thereto; means for yieldingly urging said member to a given normal position relatively to the base; manually engageable means, to move said member to a second position relatively to the base, against the urging of said yielding means; means controlling the speed of said member in returning to its normal position under the urging of said yielding means, to delay the completion of said return a predetermined time; a second movable member relatively movable to but operatively connected with the first and moved thereby to a given circuit-closing position when said first member is moved against

the urging of said yielding means; means for holding said second member in its circuit-closing position; a heating element; means for closing a circuit through the heating element when the second member is in said circuit-closing position; means for moving said second member to its initial position, to open the circuit through the heating element, when the said first member completes its return to normal position and releases the holding means; and means to govern the speed-controlling means for said first member whereby the time required by said member in returning to its normal position may be varied.

13. In a cigar lighter, a holder having a contact therein; a heating element carried by the holder; means for closing a circuit through the contact in the holder for energizing the heating element, comprising a pair of telescoping elements, one of said elements carrying a contact; manual means for moving the telescopic elements in the holder into circuit-closing position; yieldable means mounted in the holder for normally resisting said movement; means for retaining the contact-carrying element in circuit-closing position; yieldable means interposed between the telescoping elements whereby there may be relative movement between said telescoping elements; and means for releasing said retaining means whereby the contact-carrying element is moved to open the circuit.

14. In a cigar lighter, a holder having a contact therein; a heating element carried by the holder; means for closing a circuit through the contact in the holder and the heating element for energizing the heating element, comprising a pair of telescoping elements, one of said elements carrying a contact; manual means for moving the telescopic elements into circuit-closing position; spring means mounted in the holder for normally resisting said movement; means for retaining the contact-carrying element in circuit-closing position; spring means interposed between the telescoping elements whereby there may be relative movement between said telescoping elements; and heat-responsive means for releasing said retaining means whereby the contact-carrying element is moved to open the circuit.

15. In an electric cigar lighter having a holding device; an igniting unit mounted on the holding device for complete removal for use, said igniting unit including a heating element; manually operable means for closing a circuit to said heating element; and means including pneumatic timing means having a plurality of ports for automatically opening said circuit, one of said ports operating independently of the temperature of the heating element and another of said ports being rendered operative by means responsive to the temperature of the heating element.

16. In an electric cigar lighter having a holding device; an igniting unit mounted on the holding device for complete removal for use, said igniting unit including a heating element; manually operable means for closing a circuit to said heating element; and means including pneumatic timing means having a plurality of operable ports for automatically opening said circuit, one of said ports being rendered operative by means responsive to the temperature of the heating element.

17. In an electric cigar lighter having a holding device; an igniting unit mounted on the holding device for complete removal for use, said

igniting unit including a heating element; manually operable means for closing a circuit to said heating element; and means including pneumatic timing means having at least one port controlled in accordance with the temperature of the heating element for opening the circuit to the heating element.

18. An electric cigar lighter having a holder; an igniting unit mounted on the holder and completely removable therefrom for use; a heating element carried by the igniting unit; means for closing an energizing circuit to the heating element; time controlled means carried by the igniting unit and operable independently of the temperature of the heating element to open the circuit to the heating element when the heating element has attained its desired heat; and heat-responsive means acting upon the time controlled means to open the circuit should the last-named means fail.

19. An electric cigar lighter having a holder; an igniting unit mounted on the holder and adapted to be removed therefrom for use; a heating element carried by the igniting unit; means for closing an energizing circuit to the heating element; pneumatic means normally operating to open the circuit to the heating element when the lighter is ready for use; and heat-responsive means acting on the pneumatic means for opening the circuit to the heating element if the first-mentioned circuit-opening means fails to properly operate, thereby preventing the heating element from burning out.

20. In a cigar lighter, a base; a manually operable member carried by the base and movable relatively thereto; means for yieldingly urging the manually operable member to one given position on the base; a heating element; means for closing a circuit through the heating element to energize same incident to movement of the manually operable member when out of said given position, said means including a contact operable by the member, and a second contact adapted to engage said first contact; means for maintaining the circuit closed when the operable member returns to said given position in response to the urging of said yielding means, including means for movably mounting one of said contacts relatively to said base and operable member; said means for closing the circuit also including means for opening the circuit incident to heating of the element.

21. In a cigar lighter, a base; a manually operable member carried by the base and movable relatively thereto; means for yieldingly urging the manually operable member to one given position on the base; a heating element; means for closing a circuit through the heating element to energize same incident to movement of the manually operable member when out of said given position, said means including a contact operable by the member, and a second contact adapted to engage said first contact; means for maintaining the circuit closed when the operable member returns to said given position in response to the urging of said yielding means, including means for movably mounting one of said contacts relatively to said base and operable member; said means for closing the circuit also including means for opening the circuit in response to heating of the element.

22. In a cigar lighter, a base; a manually operable member carried by the base and movable relatively thereto and withdrawable therefrom; a heating element carried thereby; means for closing a circuit through the heating element to energize same incident to circuit-closing movement of the manually operable member, said means including a contact operable by said member, and a second contact adapted to engage said first contact; and means for maintaining the circuit closed during retrograde movement of the manually operable member, including means for mounting one of said contacts for movement relative to said base and said member.

10 23. In a cigar lighter, a base; a manually operable member carried by the base and movable relatively thereto and withdrawable therefrom; a heating element carried thereby; means for closing a circuit through the heating element to energize same incident to circuit-closing movement of the manually operable member, said means including a contact operable by said member, and a second contact adapted to engage said first contact; means for maintaining the circuit closed during retrograde movement of the manually operable member including means for mounting one of said contacts for movement relative to said base and manually operable member; and means responsive to the temperature of the heating element for causing the manually operable member to complete its retrograde movement and cause the circuit to be opened.

24. In a cigar lighter, a base; a manually operable member carried by the base and movable relatively thereto and withdrawable therefrom; a heating element carried thereby; means for closing a circuit through the heating element to energize same incident to circuit-closing movement of the manually operable member, said means including a contact operable by said member, and a second contact adapted to engage said first contact; and means for maintaining the circuit closed during retrograde movement of the manually operable member, including means for mounting one of said contacts for movement relative to said base and said member, said means for maintaining the circuit closed being released at a predetermined point in the retrograde movement of the manually operable member.

25. In a cigar lighter, a base; a manually operable member carried by the base and movable relatively thereto and withdrawable therefrom; a heating element carried thereby; means for closing a circuit through the heating element to energize same incident to circuit-closing movement of the manually operable member, said means including a contact operable by said member, and a second contact adapted to engage said first contact; means for maintaining the circuit closed during retrgrade movement of the manually operable member, including means for mounting one of said contacts for movement relative to said base and said member, said means for maintaining the circuit closed being released at a predetermined point in the retrograde movement of the manually operable member; and means for separating the contacts upon release of said means for maintaining the circuit closed to prevent unintentional reclosing of said circuit.

ARTHUR A. JOHNSON.
